(57) **CLAIM**

The ornamental design for an electronic device enclosure, as shown and described.

DESCRIPTION

FIG. 1 is a perspective view of an electronic device enclosure, as seen from above;

FIG. 2 is a perspective view of the electronic device enclosure, as seen from below;

FIG. 3 is a top view of the electronic device enclosure;

FIG. 4 is a bottom view of the electronic device enclosure;

FIG. 5 is a right side view of the electronic device;

FIG. 6 is a left side view of the electronic device enclosure;

FIG. 7 is a front view of the electronic device enclosure; and,

FIG. 8 is a rear view of the electronic device enclosure.

Broken lines are used to illustrate features of the electronic device enclosure which form no part of the claimed design.
